STOPPING MEANS FOR CALCULATING MACHINES

Herman Gang, Livingston, N. J., assignor to Monroe Calculating Machine Company, Orange, N. J., a corporation of Delaware.

Application April 30, 1949; Serial No. 90,623

12. Claims. (Cl. 235—62)

1

The invention relates to stopping means for motor operated calculating machines and particularly to such means wherein the operation thereof is initiated in response to the retraction of an operating key from an operation initiating position. The effective operation, however, of the stopping means is delayed, thereby permitting the machine to complete a current program of operations.

In the specific application of the invention hereinafter disclosed, the operation of the stopping means is adapted to be initiated by the devices of the invention in lieu of another normally effective initiating means when, under certain conditions, the operation of said normal means is unduly delayed or is not effected. In the intended operation of the machine, however, the operation of the normal initiating means will supersede the operation of the devices of the invention.

The preferred form of the invention is disclosed as adapted for operation in conjunction with the stopping means for a program of division and in such a machine as fully disclosed in my copending application, Serial No. 8,548 (now Patent 2,531,207). According to the aforesaid copending application, division is effected by the well-known subtract and shift method; the operation being initiated upon depression of a settable operating key.

In the normal operation of the machine, the movement of the dividend wheels is adapted to control the duration of registration, carriage shift and upon retraction of the operating key to control the stopping means. If, however, the shiftable carriage has been positioned too far toward the left, the machine will cycle an inordinate number of times before movement of the controlling dividend wheels is effected and therefore retraction of the divide key to stop the machine will not be effective within a reasonable length of time. Furthermore, should the divide key be depressed without a divisor set in the keyboard, retraction of the key will be ineffective to stop the machine as no registration will be effected in the dividend register to initiate the operation of the stopping means.

The devices of the present invention provide means which will be effective in the instances outlined above or in the event of failure of the normally effective means to initiate operation of the stopping means for other reasons. The invention, however, will best be understood from the following description with reference to the accompanying drawings in which:

2

Fig. 1 is a left side elevation of the machine showing the stopping means and the devices for initiating operation thereof in normal position.

Fig. 2 is a fragmentary front elevation of the divide and stop keys.

Fig. 3 is a left side elevation of the machine with certain of the mechanisms shown in Fig. 1 in an operated position.

Fig. 4 is an exploded perspective view showing the ratchet member and certain devices related thereto.

Division and normal stopping operation.

In a machine operating as disclosed in the afore-mentioned copending application Serial No. 8,548 (now Patent 2,531,207) and embodying an application of the invention, a program of division is initiated upon depression of a settable divide key 590 (Figs. 1, 2 and 3). Divide key 590

is held in adjusted position by a lever 719 (Fig. 2) which is pivotally mounted upon a bracket secured at the front of the keyboard. The stem of the divide key is provided with two spaced lugs and the rightwardly extending arm of lever 719 is positioned therebetween. The ends of a toggle spring 720 are attached to the rightmost end of lever 719 and to a pin fixed in the bracket at the front of the keyboard. Thus, lever 719 is biased in counterclockwise direction (Fig. 2) thereby holding divide key 590 in raised position. However, when the divide key is depressed, lever 719 is rocked clockwise thereby and the lever is then biased clockwise by spring 720, thus holding key 590 in set position.

A stop key 618 is positioned to the left of the divide key and is held in normal raised position by a suitable spring. The stem of stop key 618 is provided with a lug positioned above the leftwardly extending arm of lever 719. Therefore, when lever 719 is rocked clockwise upon depression of the divide key, the leftward arm of the lever will be raised to a position immediately adjacent the lug of the stop key. Accordingly, upon depression of the stop key, the lug thereon will contact and rock lever 719, thereby retracting divide key 590.

The stem of divide key 590 is attached at its lower end to a crank (Figs. 1 and 3) which is attached to the rightmost end of a bail 721 pivotally mounted on a shaft 591. Bail 721 is provided with an upstanding arm to which is attached the forward end of a link 722. Link 722 extends toward the rear of the machine where it is attached to one arm of a bell crank 723 (Fig. 3). When divide key 590 is depressed, bail 721 will be rocked,

thereby moving link 722 from the position shown in Fig. 1 toward the front of the machine. Link 722 is provided with a pin 722' which is adapted for operation in connection with latches 456 and 725. Latch 456 normally connects arms 454 and 455 which are rocked in unison by a cam 372 upon operation of a two phase clutch 371; which operation invariably occurs following the termination of a carriage shift. However, in the performance of the division program, according to the above noted copending application, arm 455 must not be rocked. Therefore, when link 722 is moved forwardly, pin 722' will rock latch 456 from the position shown in Figs. 1 and 3, counterclockwise against the tension of a spring, and thereby disconnect arms 454, 455. However, prior to the final operation of clutch 371, which invariably concludes a program of division, latch 456 is reengaged so that arm 455 may be rocked to perform certain normalizing operations to be hereinafter described.

The effective end of a latch lever 725 which is pivotally mounted on the framing of the machine is normally in engagement with a roller on an arm of a crank 726 (Fig. 1), fixed on a pivotally mounted shaft 616. A second crank 729 is affixed to crank 726 by a sleeve, and the two cranks and shaft 616 are biased in clockwise direction by a spring 728 attached to an arm of crank 729. When latch 725 is in normal engagement with the roller of crank 726, shaft 616 is held in counterclockwise position against the tension of spring 728. Latch 725 is normally engaged by pin 722' (Fig. 1) and therefore when link 722 is moved forwardly (not shown), pin 722' will move latch 725 out of engagement with the roller of crank 726. Accordingly, spring 728 will rock crank 729, crank 726 and shaft 616 in a clockwise direction to the position shown in Fig. 3. Another crank 732 is also fixed on shaft 616 and extends upwardly therefrom. The rearward end of a forwardly extending link 733 is attached to crank 732, and as the crank is rocked with shaft 616, link 733 is moved toward the front of the machine. As disclosed in the afore-mentioned copending application Ser. No. 8,548 (now Patent 2,531,207), the movements of cranks 726, 729 and link 733 are adapted to adjust certain controls for the division program and to initiate the operation of certain mechanisms to move clutch lever 111 in counterclockwise direction (Fig. 3), thereby engaging differential clutch mechanism 105 for subtractive registration. Furthermore, as will be hereinafter described, certain preliminary adjustments of the devices of the invention will be effected as an incident to the operation of the aforesaid registration control means to initiate the program.

The subtractive registrations will continue until a divisor set on the keyboard 10 is subtracted once more than it is contained in the corresponding portion of the dividend registered in dividend wheels 13. A negative numeral wheel reading is therefore obtained and the tens transfer mechanism will successively move wheels 13 through intermediate gears 545 from 0 to 9 as far toward the left as such transfer mechanism is provided. One of the intermediate gears 545 is located to the outside of the left hand side frame and the one step movement of this gear by the tens transfer mechanism is utilized to trip the control devices for terminating the subtractive operation by rocking a lever 31. Lever 31 is spring urged in clockwise direction and its leftmost free end is provided with a nose 31' engag-

ing a tooth space of the intermediate gear 545. The rightmost end of lever 31 normally engages a spring urged latch 25 thereby holding said latch in disengaged position. Latch 25 is mounted on the upper free end of a pivotally mounted arm 24 which is held in normal counterclockwise position (Figs. 1 and 3) by a suitable spring. Latch 25 is adapted for engagement with a shoulder at the upper free end of an arm 22 which is pivotally mounted at a common point with arm 24. Arm 22 is reciprocated clockwise from the position shown in Fig. 1 and return, once for each cycle of registration by a link 21 and crank 20 which is driven by a suitable gear train (Fig. 3) with the actuating mechanism.

Upon movement of gear 545, lever 31 will be rocked, thereby releasing latch 25 for engagement with the shoulder of arm 22. Therefore upon the next clockwise movement of arm 22, arm 24 will be rocked in unison therewith to move said arm 24 against the fixed stop 29. Arm 24 is provided with an extension 144 provided with a cam slot at its free end adapted for engagement with a pin 145 on clutch lever 111. Therefore, when arm 24 is moved against stop 29, the cam slot will move clutch lever 111 to its neutral position, thereby disconnecting the drive to the actuators. Arms 22, 24 will, thereupon, rebound from stop 29 in the reverse direction and latch 25 will be disengaged by lever 31 and clutch lever 111 engaged for additive registration. A single additive registration will be effected to correct the excessive subtraction as the tens transfer mechanism will move the leftmost wheels from 9 back to 0 thereby tripping the control devices and initiating a single order carriage shift. The initiation of the carriage shift is effected by engagement of the two phase clutch 371 for a single step of movement and upon termination of the shift, the clutch is reengaged to effect certain normalizing operations as will appear.

The retraction of divide key 590 by stop key 618 provides that the division program may be terminated when the desired number of quotient digits have been registered. Upon retraction of divide key 590, the machine will continue to calculate until the correct quotient digit has been registered in that order; thereupon carriage 2 will be shifted one order to the left and the operation terminated without calculation in that order as follows:

It will be recalled that when divide key 590 is depressed latch 456 was moved to disconnect arms 454, 455. Retraction of divide key 590 therefore will permit the recoupling of said arms by latch 456. Arm 455 is adapted for engagement with a depending lug on a link 424 which is attached at its forward end to arm 24. Therefore when the two phase clutch 371 is operated at the termination of the final shifting operation, cam 372 will rock arms 454, 455. Link 424 will therefore carry arm 24 to the fixed stop 29 and thereby disengage differential clutch 105.

If the stop key is not operated, the program of operations will continue until the carriage is shifted into its leftmost position. Upon completion of the registering operations in that order, the carriage shift mechanism will be idly operated for a single cycle. The idle operation is utilized to restore the divide key and thereupon the operation of the two phase clutch will terminate the operation in accordance with its operation upon retraction of the divide key by the stop key.

Alternate shopping operation

From the foregoing it will be noted that upon retraction of the divide key, operation of the carriage shift mechanism is necessary to stop the machine, that termination of an additive cycle of registration is necessary to initiate the carriage shift and that the termination of the subtractive and additive registrations is effected by movement of the numeral wheels to operate lever 31. If lever 31 is not operated after a given number of cycles of the registering mechanism the devices of the invention are adapted to operate said lever to terminate the subtractive operation and operate it a second time to terminate the following additive cycle of operation. The operation of the two phase clutch 371 upon termination of the carriage shift will thus stop the machine as described in connection with the operation of the stopping means when lever 31 is operated by movement of the numeral wheels.

To accomplish the above, a device has been provided which, after retraction of divide key 590 will be advanced one step of movement for each cycle of operation of the registering mechanism. The tenth cycle will effect the maximum advancement and then permit a reverse movement of the device one step; the advancement and subsequent reverse movement effecting operation of trip lever 31 to terminate minus operation of the registering mechanism. The following plus corrective cycle will effect readvancement and reverse movement of the device to again operate lever 31 to terminate the operation. The maximum number of cycles required for the registration of any quotient digit is eleven, i. e., ten negative cycles and a plus corrective cycle for the digit nine. It will be seen therefore that the devices of the invention will not interfere with the operation of the normally operable stopping means but will be operated in lieu thereof if, for reasons heretofore set forth, said normally operable means is rendered ineffective.

The device comprises a ratchet member 800 (Figs. 1, 3 and 4) having a series of teeth extending partially around its periphery. Ratchet 800 is rotatably mounted on shaft 616 between cranks 732 and 726, and is normally held in clockwise position (Fig. 1) by a spring 801 (Fig. 4). A suitable stop pin on ratchet 800 determines its normal position by engagement with the lower free end of a slide 802 (Fig. 1). Ratchet 800 is provided with a counting detent 803 and a back stop pawl 804; each of which is spring biased for engagement with said ratchet. A latching arrangement, however, normally holds pawl 804 and detent 803 out of engagement (Fig. 1) with the ratchet. Such latching is effected by a circumferentially disposed edge portion of crank 726 engaging back stop pawl 804. At its lower free end, detent 803 has slot connection with pawl 804 and is thereby also held from engagement with ratchet 800. Detent 803 is pivotally mounted at its upper end on a leftward extension of arm 22. Therefore, as arm 22 is reciprocated with each cycle of the registering mechanism, detent 803 will be raised and lowered accordingly.

The forward movement of link 722 upon depression of divide key 590 and the resulting clockwise movement (Fig. 3) of crank 726 provides for the release of pawl 804 and detent 803 from the edge portion of said crank and for the adjustment of another latching means to prevent the pawl and detent from engaging ratchet 800 at this time. To this end, the edge portion of

crank 726 is provided with a recess 805 which, upon clockwise movement of said crank, is moved into position to permit engagement of ratchet 800 by pawl and detent 804, 803. However, upon 5 the aforesaid forward movement of link 722 (which position is not shown) a pin 806 on said link will be moved into position to block pawl 804 and detent 803 from movement to engage the ratchet.

Upon retraction of divide key 590, link 722 will be moved rearwardly to normal position (Fig. 3) thereby moving pin 806 from engagement with pawl 804. Thereupon, pawl 804 and detent 803 will be moved by their springs into engagement 15 with ratchet 800; such engagement being allowed by recess 805. Ratchet 800 will be advanced step by step; the back stop pawl 804 preventing reverse movement of said ratchet. If the normal operation of the stopping means does not intervene, the operation will continue until a pin 807 on ratchet 800 is moved into engagement with the lower end of slide 802 (Fig. 3) upon the tenth step of movement of said ratchet.

Slide 802 has slot and pin mounting on the 25 framing of the machine and is thereby adapted for movement upwardly from its normally lowered position. A rightwardly extending arm at the upper end of slide 802 underlies a pin 134' on the rightwardly extending arm of a lever 134. Lever 134 is spring biased in clockwise direction and is provided with a pivotally mounted trip pawl 136 on its leftwardly extending arm. Pawl 136 is spring urged in counterclockwise direction but is normally held in the position shown in 30 Fig. 1 by engagement with a pin on the framing of the machine. When in normal position, a lug of pawl 136 is positioned to the right and above a depending lug of lever 31. Therefore, upon the tenth step of movement of ratchet 800, 40 slide 802 will be moved upwardly and lever 134 rocked in counterclockwise direction. Pawl 136 will thereupon be allowed counterclockwise movement to position its lug beneath the lug of lever 31 (Fig. 3). Furthermore, upon the tenth step 45 of movement, the untoothed portion of ratchet 800 will be moved into engagement with back-stop pawl 804. Therefore, upon the return downward movement of detent 803, ratchet 800 will be allowed one step of reverse movement by its 50 spring 801. This will permit spring urged lever 134 to be rocked in clockwise direction and slide 802 to drop back to its normal lowered position. The lug of pawl 136 engaging the lug of lever 31 will therefore rock said lever and thus release 55 latch 25 for engagement with the shoulder of arm 22 to terminate the subtraction registration. Upon the following additive cycle of the registering mechanism, ratchet 800 will be readvanced, 60 thereby terminating additive registration, which termination will initiate the final operation of the carriage shift mechanism. The operation of clutch 371 will effect the normalizing of the devices as follows:

The rearward movement of link 722 upon retraction of the divide key will permit the recoupling of arms 454, 455 by latch 456 as heretofore described. In its unset position (Fig. 3), latch 725 is positioned with its under side resting upon the roller of crank 726 and its upper edge moved into a position adjacent a roller on arm 455. When clutch 371 is operated the recoupled arms 454, 455 will be rocked in clockwise direction by cam 372. The roller on arm 455 will move latch 725 clockwise to normal latching 75 position thereby moving crank 726 and the

associated parts counterclockwise to normal. The movement of crank 726 to normal will engage the leftmost edge of recess 805 with pawl 804, thereby camming said pawl and detent outwardly from engagement with ratchet 800, thereby releasing said ratchet which will then be moved clockwise by spring 801 to normal. In the normal operation of the machine, it will be apparent that the normalization of crank 726 will be effective to release the partially advanced ratchet 800 in like manner.

Although I have shown and described the invention as adapted for operation in conjunction with the stopping means for a particular program of operations, it will be apparent that the invention may be adapted for use in conjunction with other stopping means for other operations. For example, where a common drive means operates to effect any selected one of a plurality of operations and is started as an incident to the selection, a stopping means for the drive means could be controlled by the delay devices of the invention and thereby permit a selected series of operations to be performed without stopping and starting the drive between each operation. Other applications of the invention may present themselves to those skilled in the art. The invention, therefore, is not to be restricted to the specific embodiment disclosed except as required by the spirit of the appended claims.

I claim:

1. In a motor driven calculating machine having cyclically operable registering means, registration control means for initiating cyclic operation of the machine including a retractable operating key and means operable to terminate operation of the machine; means operable in response to the retraction of said operating key to initiate operation of said terminating means comprising a device adapted to be advanced from a normal position, a spring for urging said device to normal position, normally disengaged adjustable driving means driven in timed relationship with said registering means for advancing said device incrementally against the tension of its spring, means for engaging said driving means with said device upon operation and subsequent retraction of said operating key, a contact member on said device, means operable by said contact member upon a given advance of said device to initiate operation of said terminating means and means operable in response to the operation of said terminating means to disengage said driving means.

2. A motor driven calculating machine according to claim 1 wherein the means for engaging the driving means with the device comprises a spring having connection with said driving means, latching means for holding said driving means in disengaged position against the tension of said spring and means for disabling said latching means upon operation and subsequent retraction of the operating key and wherein the means operable to disengage said driving means comprises means operable in response to the operation of the terminating means to enable said latching means.

3. A motor driven calculating machine according to claim 2 wherein the latching means comprises an adjustable member normally holding the driving means in disengaged position and a second adjustable member normally ineffectively positioned for holding said driving means in disengaged position, and wherein the means for disabling said latching means com-

5 prises means for adjusting said first and second named members to ineffective and effective positions respectively upon operation of the operating key and for adjusting said second named member to ineffective position upon retraction of said key.

4. A motor driven calculating machine according to claim 3 wherein the means to disengage the driving means comprises the first named member of the latching means.

5. In a motor driven calculating machine having cyclically operable registering means, registration control means for initiating cyclic operation of the machine including a retractable operating key and means operable to terminate operation of the machine; means operable in response to the retraction of said operating key to initiate operation of said terminating means comprising a ratchet member adapted to be advanced from a normal position, a spring for urging said ratchet member to normal position, an adjustable counting detent driven in timed relationship with said registering means for advancing said ratchet member step by step against the tension of its spring, a back stop pawl for said ratchet member, spring means tending to engage said detent with said ratchet member, latching means for holding said detent in disengaged position, means for disabling said latching means upon operation and subsequent retraction of said operating key, a contact member on said ratchet member, means operable by said contact member upon a given advance of said ratchet member to initiate operation of said terminating means and means operable in response to the operation of said terminating means to release said back stop pawl and said detent and to enable said latching means.

40 6. A motor driven calculating machine according to claim 5 wherein the latching means comprises an adjustable member normally holding the detent in disengaged position and a second adjustable member normally ineffectively positioned for holding said detent in disengaged position, and wherein the means for disabling said latching means comprises means for adjusting said first and second named members to ineffective and effective positions respectively upon operation of the operating key and for adjusting said second named member to ineffective position upon retraction of said key.

45 7. A motor driven calculating machine according to claim 5 wherein the ratchet member is provided with a toothed section and an adjoining toothless section; said toothed section being engaged by the back stop pawl during the advance of said ratchet member toward the given advanced position and being moved beyond said pawl during the last step of movement of said ratchet member to the given advanced position thereby engaging said toothless section with said pawl and permitting subsequent reverse movement of said ratchet member and readvancement thereof to said given advanced position.

50 8. In a motor driven calculating machine having a dividend register, a quotient register, selecting mechanism, cyclically operable registering means, division control means for dividing an amount registered in said dividend register by an amount set in said selecting mechanism and for automatically registering a plural figure quotient including a retractable operating key for initiating the operation, means operable to terminate operation of the machine and means operable by the dividend register to initiate op-

eration of said terminating means in response to the retraction of said operating key upon the next completion of a quotient figure registration; a ratchet member adapted to be advanced from a normal position, a spring for urging said ratchet member to normal position, an adjustable counting detent driven in timed relationship with said registering means for advancing said ratchet member step by step against the tension of its spring, a back stop pawl for said ratchet member, spring means tending to engage said detent with said ratchet member, latching means for holding said detent in disengaged position, means for disabling said latching means upon operation and subsequent retraction of said operating key, a contact member on said ratchet member, means operable by said contact member upon a given advance of said ratchet member to initiate operation of said terminating means; the steps of advancement being of sufficient number to permit cycling of the machine a number of times sufficient to permit registration of any quotient digit and means operable in response to the operation of said terminating means to release said back stop pawl and said detent and to enable said latching means.

9. A motor driven calculating machine according to claim 8 wherein the ratchet member is provided with a toothed section and an adjoining toothless section; said toothed section being engaged by the back stop pawl during the advance of said ratchet member toward the given advanced position and being moved beyond said pawl during the last step of movement of said ratchet member to the given advanced position, thereby engaging said toothless section with said pawl and permitting subsequent reverse movement of said ratchet member and readvancement thereof to said given advanced position.

10. In a motor driven calculating machine having cyclically operable registering means, registration control means for initiating cyclic operation of the machine, including a retractable operating key and means operable to terminate the operation of the machine; means operable in response to the retraction of said operating key to initiate operation of said terminating means comprising a device adapted to be advanced from a normal position and upon a given advance effective to initiate operation of said terminating means, normally disengaged driving means driven in timed relation with said registering means for advancing said device incrementally, means responsive to the operation and subsequent retraction of said operating key for engaging said driving means, and means operable in response to the operation of said terminating means to disen-

gage said driving means and to restore said device to normal.

11. In a motor driven calculating machine having cyclically operable registering means, registration control means for initiating cyclic operation of the machine including a retractable operating key, means operable to terminate operation of the machine and means normally effective in response to the retraction of said operating key to initiate operation of said terminating means; alternate means operable in response to the retraction of said operating key to initiate operation of said terminating means comprising a device adapted to be advanced from a normal position and upon a given advance effective to initiate operation of said terminating means, normally disengaged driving means driven in timed relation with said registering means for advancing said device incrementally, means responsive to the operation and subsequent retraction of said operating key for engaging said driving means, and means operable in response to the operation of said terminating means to disengage said driving means and to restore said device to normal.
12. In a motor driven calculating machine having a register, cyclically operable actuating mechanism therefor, means for initiating operation of said actuating mechanism including a retractable operating key and means operable to terminate operation of said actuating mechanism; the combination with means settable upon retraction of said operating key and responsive to registration by said actuating mechanism to initiate operation of said terminating means of alternate means for initiating the terminating operation comprising a device adapted to be advanced from a normal position and upon a given advance effective to initiate operation of said terminating means, normally disengaged driving means driven in timed relation with said actuating mechanism for advancing said device incrementally, means responsive to the operation and subsequent retraction of said operating key for engaging said driving means, and means operable in response to the operation of said terminating means to disengage said driving means and to restore said device to normal.

HERMAN GANG.
